US00D789297S

(12) **United States Design Patent** (10) **Patent No.:** **US D789,297 S**
Dobler (45) **Date of Patent:** **** Jun. 13, 2017**

(54) **CONNECTOR**

(71) Applicant: **NEUTRIK AG**, Schaan (LI)

(72) Inventor: **Oliver Dobler**, Eschen (LI)

(73) Assignee: **Neutrik AG**, Schaan (LI)

(**) Term: **15 Years**

(21) Appl. No.: **29/555,242**

(22) Filed: **Feb. 19, 2016**

Related U.S. Application Data

(62) Division of application No. 29/487,575, filed on Apr. 10, 2014, now Pat. No. Des. 755,720.

(57) **CLAIM**

The ornamental design for a connector, as shown and described.

DESCRIPTION

FIG. 1 is a perspective view of a connector showing my design;

FIG. 2 is a left side elevation view thereof;

FIG. 3 is rear elevation view thereof;

FIG. 4 is front elevation view thereof;

FIG. 5 is a top plan view thereof;

FIG. 6 is a right side elevation view thereof; and,

FIG. 7 is a bottom plan view thereof.

The broken line portion of the figure drawings is included to show unclaimed subject matter only and forms no part of the claimed design.
